MAGNETIC TOY

Leonard Macpherson, Los Altos, Calif., assignor to
Rathcon, Inc., Dallas, Tex.

Filed Dec. 11, 1969, Ser. No. 20,463

Term of patent 14 years

Int. Cl. D19—08

U.S. Cl. D25—1

FIG. 1

FIG. 2

FIG. 3

FIG. 4

FIG. 1 is a top plan view of the magnetic toy showing my new design;

FIG. 2 is a front perspective view thereof;

FIG. 3 is a side elevation view thereof; and

FIG. 4 is a side elevation view thereof.

The bottom of the magnetic toy is substantially the same as the top plan view of the mounting plate as shown in FIG. 1.

I claim:

The ornamental design for a magnetic toy, as shown.
